Patented Sept. 20, 1921.

UNITED STATES PATENT OFFICE.

GARABED OHANIAN, OF PATERSON, NEW JERSEY, ASSIGNOR OF ONE-HALF TO
HAROOTUN CHEKENIAN, OF PATERSON, NEW JERSEY.

HAIR-BRUSH.

1,391,207.

Specification of Letters Patent. Patented Sept. 20, 1921.

Application filed March 17, 1921. Serial No. 452,918.

To all whom it may concern:

Be it known that I, GARABED OHANIAN, a citizen of the United States, residing at Paterson, in the county of Passaic and State of New Jersey, have invented certain new and useful Improvements in Hair-Brushes; and I do declare the following to be a full, clear, and exact description of the invention, such as will enable others skilled in the art to which it appertains to make and use the same.

This invention relates to an improved hair brush, and has for its object, to provide a device of this class wherein the head and handle is made up of hingedly connected separable sections, one of which is formed in its inner face with a plurality of recesses shaped to conform to and receive different kinds of toilet articles or other implements, thereby enabling the brush to serve the additional function of an implement holder.

Another and important object of the invention is to provide a brush head and handle of the aforesaid construction wherein each recess is formed at one end with an undercut forming a shoulder beneath which one end of the article therein extends, separate, pivoted fasteners co-acting with the opposite ends of the article to retain them in the recesses, and springs, preferably flat ones, being arranged in the bottoms of the recesses to automatically eject the articles from the recesses when the fasteners are released. The employment of these springs is advantageous since it becomes unnecessary to pry or otherwise force the articles from the recesses as would otherwise be necessary, as these articles have their outer faces flush with the face of the brush section in which the recesses are formed to permit the sections to be folded into a close and tight engagement with one another.

A further object of the invention is to provide a brush head and handle of the aforesaid construction, wherein the cover section is equipped with a mirror.

Other objects and advantages of the invention will be apparent during the course of the following description.

In the accompanying drawings forming a part of this specification and in which like numerals are employed to designate like parts throughout the same:

Figure 1 is a side elevational view of a

brush constructed in accordance with this invention, showing the separable sections connected together.

Fig. 2 is a top plan view of the brush showing the sections separated to disclose the toilet articles and the manner in which they are held in place.

Figs. 3 and 4 are sectional views taken on the planes of the lines 3—3 and 4—4 respectively of Fig. 2.

The brush I employ is, in general appearance, like brushes commonly used. I have conceived of the idea of constructing the head and handle portion of the brush of separable sections 1 and 2 of corresponding separable sections, one of which is formed in its inner face with a plurality of recesses shaped to conform to and receive different kinds of toilet articles or other implements, thereby enabling the brush to serve the additional function of an implement holder.

Another and important object of the invention is to provide a brush head and handle of the aforesaid construction wherein each recess is formed at one end with an undercut forming a shoulder beneath which one end of the article therein extends, separate, pivoted fasteners co-acting with the opposite ends of the article to retain them in the recesses, and springs, preferably flat ones, being arranged in the bottoms of the recesses to automatically eject the articles from the recesses when the fasteners are released. The employment of these springs is advantageous since it becomes unnecessary to pry or otherwise force the articles from the recesses as would otherwise be necessary, as these articles have their outer faces flush with the face of the brush section in which the recesses are formed to permit the sections to be folded into a close and tight engagement with one another.

A further object of the invention is to provide a brush head and handle of the aforesaid construction, wherein the cover section is equipped with a mirror.

Other objects and advantages of the invention will be apparent during the course of the following description.

In the accompanying drawings forming a part of this specification and in which like numerals are employed to designate like parts throughout the same:

Figure 1 is a side elevational view of a

gagement with one another, the various recesses are made sufficiently deep to cause the outer faces of the toilet articles to lie flush with the face of the section in which the recesses are formed. Furthermore, the cover section is formed in its inner face with a number of pockets or other recesses to receive the latches 7 or other projections on the first named section. Since the various articles are flush with the inner face of the section 1, it would be necessary to pry them, by means of a suitable instrument, out of the recesses in order to use them. To overcome this disadvantage and to render my device more desirable and effective, I arrange flat springs 9 in the bottoms of the various recesses 4 and permit the free ends of these springs to bear against the under faces of the toilet articles as better shown in Fig. 3. Hence, it will be seen that as soon as a latch is released, the spring acting on the article held by that latch, will automatically eject the article from the recess so that the article can be gripped and removed for use. It may be added that by exerting spring pressure on the article, the ends of the latter coacting with the latches will bear tightly against said latches to prevent them from accidentally swinging on their pivots and permit accidental displacement of the articles when the sections 1 and 2 are swung open. This advantage gives the springs an additional and important function. While on the description of the bristle-carrying section 1, I deem it advisable to point out that the handle portion thereof is equipped near its free end, with a recess 10 for reception of a powder container or the like, and that this recess is closed by a sliding plate 11. Referring now to the cover section 2, it will be seen that it is equipped on its inner face with a mirror 12 and is equipped with a suitable spring-pressed latch 13 for coaction with the eye 14 on the section 1. To assist in retaining the section in a closed position, that is in the position disclosed in Fig. 1, I may make use of additional locking means in the form of a pivoted hook 15 and

headed stud 16, these being carried by the handle portion of the two sections. I wish it to be understood that the locking means for holding the sections closed, may vary in design.

A careful consideration of the description taken in connection with the accompanying drawings is thought to be sufficient to enable the reader to obtain a clear understanding of the same. Therefore, a more lengthy and detailed description is deemed unnecessary.

I claim:

1. A brush of the type described comprising separable hingedly connected sections shaped to form the head and handle, one of said sections having bristles on its outer face and having a plurality of recesses formed in its inner face, each of said recesses being shaped to receive a toilet article and having its wall undercut at one end to form a shoulder, beneath which one end of the article extends and is held, fasteners secured to the aforesaid inner face near the opposite ends of the recesses, being adapted to engage the articles and hold them in the recesses, and springs in the latter to automatically eject the articles from the recesses when the fasteners are released.

2. A brush head and handle made up of hingedly connected separable sections corresponding in shape, one of said sections being formed in its inner face with a plurality of comparatively shallow recesses, each one being shaped to conform to the outline of a toilet article which is to be placed therein, one of the end walls of the recesses being undercut to provide shoulders, beneath which one end of the articles are to extend, pivoted latches co-operative with the other ends of the articles, and flat springs in the bottoms of the recesses to automatically eject the articles therefrom when the latches are released.

In testimony whereof I have hereunto set my hand.

GARABED OHANIAN.
